His Attorney.

UNITED STATES PATENT OFFICE

JAMES A. O'NEIL, OF LYNN, MASSACHUSETTS, ASSIGNOR TO GENERAL ELECTRIC COMPANY, A CORPORATION OF NEW YORK

LAMP STRUCTURE

Application filed December 2, 1927, Serial No. 237,281. Renewed May 19, 1930.

My invention relates to lamp structures. More particularly it relates to a type of structure which is adapted for use in connection with electric lamps. More particularly the 5 type of structure is especially adapted for use in connection with the so-called highway lighting units. Among the objects of my invention are to provide improved means for mounting the canopy of the unit, to provide 10 improved means for mounting a light-modifying element within the unit such as a so-called refractor, or a reflector, or the like. However, the various features of the invention will be more readily understood from 15 the following specification and claims, reference being had to the accompanying drawing in which Fig. 1 shows the upper portion of the lighting unit comprising the features of the invention. This figure is shown partly 20 in section. Fig. 2 is an enlarged plan view of the elements of the mounting means inside of the globe with the canopy removed. In this view is shown the supporting structure of the canopy holder and of the refractor 25 holder, which structure in turn is supported upon the rim of the globe of the unit, only a portion of the globe being shown in dotted lines. Fig. 3 shows the canopy holder and its supporting structure in perspective. The 30 dotted lines indicate the canopy holder in its raised position to enable the removal of the refractor elements from the supporting structure.

Referring more in detail to the drawing 35 it will be seen that the unit is provided with a canopy 2 and a globe 3. Within the globe is located an electric lamp 4, which lamp is surrounded by a light-modifying element 5 which may be in the form of the well-known refractor. In the type of unit shown the globe supports a ring 6 which may be of any suitable material such as metal. This ring is provided with a number of L-shaped elements 7, 8, 9, by means of which the ring 6 is hung upon the rim of the globe. The elements are provided with screws 10, 12, 11 respectively by means of which the element 6 is clamped to the rim of the globe. The ring 6 is further provided with a hinged strut 45 element 13 for supporting the canopy 2. The element 13 is provided at the top with a stud 14. It will be seen that the upper end of the stud is threaded in order to receive the pinnacle 15. This pinnacle is used for clamping the canopy 2 against the globe 3. It will be seen that the strut 13 is hinged on one side of the ring, Fig. 3, and on the opposite side this strut may be latched in an opening in the element 6. Referring to Fig. 1, it will be 50 seen that the refractor element 5 is supported by the element 16 which in turn is provided with a stud 17, the latter being if desired spot-welded or otherwise secured to the element 16. The stud 17, furthermore, is provided with a nut 18 to which there are secured three slanting radial arms 19, 20, 21, the arms being secured to the nut by means of screws 22, 23, 24, respectively. The forward ends of these arms are provided with 55 adjustable elements 25, 26, 27, respectively, which elements when once adjusted are clamped to their respective arms by means of the screws 28, 29, 30, respectively. The elements 25, 26, 27, as shown in Fig. 2, rest upon the ring 6 and the forward ends of these elements are bent so as to engage the outer side of the ring to prevent the structure as a whole 60 from slipping off of the ring. Otherwise the refractor 5 might fall and strike the lamp 4 as well as the globe 3. In order to lock 65 the nut 18 I provide the stud 17 with a wing nut 31. It will be seen, therefore, that with the type of unit described after the strut 13 has been raised as indicated in Fig. 3, the refractor, together with its supporting structure about the stud 17, may be lifted through the ring 6 whenever it becomes necessary to do so. Furthermore, by the provision of the wing nut 31 and of the nut 18 the position 70 of the refractor 5 may be adjusted with respect to the lamp 4.

It will be seen, therefore, that I provide a new structure for a lighting unit which is simple, cheap to construct, and which gives ready access to the internal sections of the unit with a minimum amount of inconvenience. The new type of construction makes the lamp itself readily accessible in view of the easy and ready means for enabling the 75 80 85 90 95 100

removal of the refractor and its supporting structure.

It will be understood that whereas I have disclosed my invention by illustrating a specific embodiment in the drawing, I do not wish to be limited to the particular structure shown and described, inasmuch as I contemplate variations and modifications within the scope of the claims contained herein.

10 What I claim as new and desire to secure by Letters Patent of the United States, is:—

15 1. In a lighting unit, a globe having an opening, a ring, means for supporting the ring in said opening, a canopy, means for securing said canopy to the globe, said means comprising an arch with one end thereof in engagement with said ring at one point and with the other end thereof in engagement with the ring at another point, said canopy being provided with a top opening, a pin at the top of the arch which projects through said opening, a pinnacle element, and means for fastening the pinnacle element to said pin over said opening in the 25 canopy.

20 2. In a lighting unit, a globe having an opening, a ring, means for supporting the ring in said opening, a canopy, means for securing said canopy to the globe, said means comprising an arch with one end thereof in engagement with said ring at one point and with the other end thereof in engagement with the ring at another point, one of said ends being hinged to the ring and the other 25 of said ends detachably engaging the ring, said canopy being provided with a top opening, a pin at the top of the arch which projects through said opening, a pinnacle element, and means for fastening the pinnacle element to said pin over said opening in the 40 canopy.

25 3. In a lighting unit, a globe having an opening, a ring, means for supporting the ring in said opening, a canopy, means for securing said canopy to the globe, said means comprising an arch with one end thereof in engagement with said ring at one point and with the other end thereof in engagement with the ring at another point, said 30 canopy being provided with a top opening, a pin on the arch which projects through said opening, a pinnacle element, means for securing the pinnacle element to said pin over said opening in the canopy, and means 35 for supporting a light-modifying element in position within the globe, said means comprising a spider element with radial arms supported by said ring.

40 4. In a lighting unit, a globe having an opening, a ring, means for supporting the ring in said opening, a canopy, an arch supported by said ring, said canopy being provided with a top opening, a pin on the arch which projects through said opening, a pinnacle element, means for securing said pin-

nacle element to said pin to clamp the canopy to the globe, and means for supporting a light-modifying element in position within the globe, said means comprising a spider element with radial arms supported by said ring, said arms being each formed of a plurality of elements adjustably related to each other for regulating the length of said arms.

70 In witness whereof, I have hereunto set my hand this 29th day of November, 1927.

75 JAMES A. O'NEIL.
